UNITED STATES PATENT OFFICE

JAMES W. GEARHART, OF FRESNO, CALIFORNIA

DOOR SECURING DEVICE

Application filed August 4, 1930. Serial No. 472,817.

This invention relates to improvements in door securing devices, and has particular reference to a portable device, which may be carried in the pocket, for securing a door which 5 may or may not be provided with a lock.

The principal object of this invention is to produce a portable device which may be attached to any door having a latch for the purpose of securing the same against being 10 opened from the outside, defeating the "master" key, pass key, and the efforts of burglars and unscrupulous persons in picking locks, and also preventing the intrusion of anyone into a hotel, apartment or other room.

15 A further object is to provide means in the formation of the portable device to compensate for various sizes of spaces between the door and door jamb.

20 A further object is to produce a portable device of this character which is simple in construction, economical to manufacture, highly efficient in use, and which is durable enough to resist heavy strains.

25 Other objects and advantages will be apparent during the course of the following description.

In the accompanying drawings forming a part of this specification and in which like numerals are employed to designate like 30 parts throughout the same,

Figure 1 is a perspective view of my device,

Figure 2 is a view similar to Figure 1, with the device turned on its axis, 180°,

35 Figure 3 is a cross sectional view of the line 3—3 of Figure 2,

Figure 4 is a cross sectional view on the line 4—4 of Figure 2,

40 Figure 5 is a top plan view of my device showing the manner in which the same is applied to the door before the same is closed, and

45 Figure 6 is a view similar to Figure 5, but showing the door in closed position, and the device in a securing position.

There are many doors which are not provided with locks, and there are other doors which are provided with locks which may be 50 opened with a master key or pass key or broken away, or easily picked, and it is to ac-

commodate doors of this character that applicant has devised his portable securing device whereby the user may effectively secure the door against opening from the outside.

The device is of a portable detachable nature and affords protection to travelers who desire privacy against the entry of persons to a room, or who do not wish to trust themselves or their valuables to the conventional locking devices employed.

In the accompanying drawings wherein for the purpose of illustration is shown a preferred embodiment of my invention, the numeral 5 designates a securing plate having a hooked end 6. At 7 I have shown a lug which is bolted as at 8 or otherwise secured to the plate 5 and through which a rod 9 passes. This rod is threaded as at 11, which threads are adapted to engage threads formed within the lug 7. A knurled head 12 serves to rotate the rod 9, the purpose of which will be later seen. This rod 9 has rotatably secured thereto a slider 13, the cross section of which is channel shaped as shown in Figure 4. This slider is slidably secured to the plate 5 and is provided with a spring 16 the end of which bears against the plate 5 as at 17, (see Figure 3). This action tends to keep the ends of the plate and the slider spaced apart, the purpose of which will later 80 be seen. The slider 13 has a bent end 18 which is adapted to abut one side of the latch casing as is shown in Figure 6.

The manner of using my device is as follows:

The end 18 is inserted at A, the latch bolt having been withdrawn into the latch by a turn of the door knob. The door is then gently closed until the hooked end 6 engages in the opening B, or door strike or latch receptacle. The door is then completely closed, the end 18 then being in aperture A and the hooked end 6 being in aperture B. As soon as the door has been closed, the knurled head 12 is rotated so that the threads 11 of the rod 9 engage the threads in the lug 7, with the result that due to the action of the spring 16, the two ends 6 and 18 will be held in their proper position. It will now be apparent that any pressure upon the door from the 100

outside, such as would move the door toward the right of the drawings as shown in Figure 6, will be resisted through the fact that the slider 13 is being rigidly held by the threaded connection between the rod and the lug.

5 While I have shown a threaded arrangement of the rod 9 to effect a movement of the slider 13, it is obvious that a trip or like arrangement might also be employed to effect an actuation of the slider to thus provide an effective locking operation of the door securing device.

10 It is to be understood that the form of my invention herewith shown and described is to be taken as a preferred example of the same and that various changes relative to the material, size, shape and arrangement of parts may be resorted to without departing from the spirit of the invention or the scope 15 of the subjoined claims.

20 Having thus described my invention, I claim:

25 1. In a portable device of the character described, a plate having a hooked-extremity, adapted to be received in a recess formed in the door jamb, a lug secured to said plate, a rod slidable in said lug, a portion of said rod being threaded and adapted to engage threads formed in said lug, a slider slidably 30 secured to said plate, said slider having a bent end adapted to be received in the latch opening of a door, the opening being in alignment with the recess of the door jamb and spring means interposed between said slider 35 and said plate for moving the ends of said plate and said slider away from each other.

40 2. A portable device of the character described comprising a plate having a hooked extremity adapted to engage a recess formed in a door jamb, a lug secured to said plate, a rod slidably and threadedly engaged by said lug, a slider rotatably secured to said rod and slidable on said plate, said slider having a slot formed therein and provided with a bent end adapted to engage a recess formed 45 in a door, and a spring extending thru the slot of said slider and having its free end engaging said plate whereby the extremity of said plate and said slider will be moved away from each other.

50 In testimony whereof I affix my signature.

JAMES W. GEARHART.
